UNITED STATES PATENT OFFICE.

LEONELLO BRUNETTI, OF SAN FRANCISCO, CALIFORNIA.

TOWER.

Application filed June 14, 1926. Serial No. 115,891.

This invention relates to a receptacle designed for use as a container for trash or the like and adapted to be positioned at street corners so that persons passing by may drop 5 newspapers, boxes or other trash in the receptacle and the streets kept clean from all foreign matter.

Another object of the invention is to provide a receptacle of this character having an 10 inclined bottom adapted to direct the material contained in the receptacle, towards the discharge opening thereof so that the receptacle may be easily emptied.

A still further object of the invention is 15 to construct the device so that it may be used for marking the streets.

With the foregoing and other objects in view which will appear as the description proceeds, the invention resides in the combination 20 and arrangement of parts and in the details of construction hereinafter described and claimed, it being understood that changes in the precise embodiment of the invention herein disclosed, may be made without departing in the scope of what is claimed, without departing from the spirit of the invention.

Referring to the drawing:

Figure 1 is a front elevational view of a receptacle constructed in accordance with 30 the invention.

Figure 2 is a vertical sectional view through the receptacle.

Figure 3 is a plan view thereof.

Figure 4 is a transverse sectional view 35 taken on line 4-4 of Figure 1.

Referring to the drawing in detail, the reference character 5 indicates the body portion of the receptacle which may be constructed of suitable plastic material such as 40 concrete or the like and provided with an inclined bottom 6 that inclines towards the front wall 7 of the receptacle.

The front wall 7 is formed with a cut out portion defining the discharge opening of 45 the receptacle which discharge opening is closed by means of the hinged closure 8 which is supplied with a suitable latch 9 for normally holding the closure in its closed position.

50 The top or cover for the receptacle is removable and is indicated by the reference character 10, the same being slightly larger

than the body portion of the receptacle so that the edges thereof extend beyond the walls of the body portion as clearly shown 55 by Figure 2.

Depressions such as indicated at 11 are formed in the upper edge of the body portion 5 and at the corners thereof, which depressions receive the bosses 12 formed on 60 the cover 10 so that movement of the cover 10, under ordinary conditions will be prevented.

Cut out portions 13 and 14 are formed in opposite sides of the cover 10, the cut out 65 portion 13 being larger than the cut out portion 14 so that a shovel may be inserted through the cut out portion to deposit trash in the receptacle. On positioning the receptacle, the cut out portion 14 will be arranged 70 adjacent to the sidewalk so that persons walking along the sidewalk may deposit trash in the receptacle through the cut out portion 14.

The reference character 15 indicates 75 hinged closures adapted for closing the cut out portions, the closures being formed preferably of metal and provided with downwardly extended flanges 16 formed along the edges thereof, which flanges are adapted 80 to fit in the grooves 17 formed adjacent to the openings so that the hinged closures will be water-proof, and the outer surfaces thereof may lie flush with the outer surfaces of the cover 10 presenting a neat appearance. 85

In order that the closures may be conveniently operated, handles 18 are provided thereon to be gripped by the person operating the closures.

The cover 10 is inclined so that it will 90 shed water and prevent water from passing into the receptacle.

Extending from the central portion of the cover 10 is a rod 19 which is provided at 95 its upper end with a paddle which may be supplied with suitable indicating characters indicating the names of the streets where the receptacle is positioned, or indicating characters may be placed thereon to indicate time allowed for parking or other regulations concerning motor vehicle traffic.

I claim:

A deposit and collection receptacle including a body portion, a cover for the body por-

tion, said cover having openings formed therein, said cover having grooves surrounding the openings, hinged closures formed of sheet material, normally covering the openings, said hinged closures having depending flanges fitted in the grooves, said cover having its lower edge extended beyond the side

walls of the receptacle, and a hinged closure for normally closing the lower portion of the body portion. 10

In testimony that I claim the foregoing as my own, I have hereto affixed my signature.

LEONELLO BRUNETTI.
